UNITED STATES PATENT OFFICE.

DANIEL C. FLETCHER, OF GRAND RAPIDS, MICHIGAN.

FOLDING IRONING-TABLE.

SPECIFICATION forming part of Letters Patent No. 337,389, dated March 9, 1886.

Application filed October 2, 1885. Serial No. 178,857. (No model.)

To all whom it may concern:

Be it known that I, DANIEL C. FLETCHER, a citizen of the United States of America, and residing at the city of Grand Rapids, in the county of Kent and State of Michigan, have invented a new and useful Improvement in Folding Ironing-Tables, of which the following is a specification, reference being had to the accompanying drawings.

10 My invention relates to the construction of an ironing-table having a suitable top and provided with hinged legs, which may be folded up underneath the top, so as to occupy less space when not in use.

15 Referring to the drawings, Figure 1 is a side elevation of my improved table standing ready for use. Fig. 2 is a front end view of the same.

20 Similar letters of reference refer to corresponding parts throughout the several figures.

A represents the top of the table, which may be of any desired size or form. Hinged to the under side of A are two sets of folding legs, B and C, braced in pairs and passing 25 obliquely downward to the floor fore and aft, C being inclosed in B. At the point of intersection is placed the brace E, rigidly secured into B. Brace E takes into the notch D in the set C and holds them braced and secured, 30 as shown in Fig. 1, for the purpose of preventing any longitudinal tipping. A third set of legs, F F, not braced together, are hinged

to said top at a point about midway between the two sets already described, and are arranged to cross each other and pass diagonally 35 athwart underneath to the floor, as shown in Fig. 2, passing between the two legs of the set C, and rest upon the floor upon the side opposite to which they are hinged. They may also be provided with hinges for folding, as 40 shown at cc, Fig. 2. This third set is designed to prevent any lateral tipping or rocking of the table when in use.

To fold the table, lift the end of the top sufficiently to disengage the brace E from the 45 notch D, when the legs may be easily folded.

Having thus described my invention, what I claim, and desire to secure by Letters Patent of the United States, is—

The combination, with the top A, of the 50 two sets of legs B and C, braced in pairs and hinged at their upper ends to the top A and arranged to pass through each other obliquely downward fore and aft, and provided with the notch D, arranged to receive the brace E, and 55 the legs F F, hinged to the top and arranged to pass each other obliquely downward athwart the top A and through the set C, and having the hinges cc, all arranged substantially as described, and for the purposes set forth.

DANIEL C. FLETCHER.
